UNITED STATES PATENT OFFICE.

GEORGE W. MIDDLETON, OF APPLING, GEORGIA.

CHIMNEY-SWEEPER.

SPECIFICATION forming part of Letters Patent No. 589,012, dated August 31, 1897.

Application filed June 2, 1897. Serial No. 639,144. (No model.)

To all whom it may concern:

Be it known that I, GEORGE W. MIDDLETON, residing at Appling, in the county of Columbia and State of Georgia, have invented a new and useful Chimney-Sweeper, of which the following is a specification.

This invention is a new and useful device for cleaning chimneys either from the top or the bottom, though it is preferably employed for cleaning a chimney from the bottom, the object being to provide an exceedingly cheap and simple device which can be kept in every house, quickly set up whenever desired, and operated by the housemaid or servant.

Another object is to provide a device which can be quickly and easily fitted to any size or shape of fireplace.

With these various objects in view my invention consists, essentially, of a bar provided with adjustable feet and adapted to be fitted in the fireplace, a rotary brush-shaft journaled in the said bar and extending up the chimney, and means arranged upon the bar for rotating the brush while held up the chimney, whereby the said chimney is thoroughly swept.

The invention consists also in certain details of construction and novelties of combination, all of which will be fully described hereinafter, and pointed out in the claims.

In the drawings forming a part of this specification, Figure 1 is a view showing the practical application of my invention. Fig. 2 is a detail view showing the mode of operation. Fig. 3 is a detail perspective view of the device, the adjustable feet being detached.

In the practical embodiment of my invention I employ a bar A, which may be constructed of wood or metal, as desired, and fitted upon each end of the said bar are the metallic feet B, said feet being slotted longitudinally, as shown at B', in order to slide freely upon the ends of the bar, the screws C passing through the slots, and upon the outer ends of the said screws are arranged the winged nuts D, whereby the feet can be securely held after being properly adjusted.

A vertical shaft E is journaled centrally of the bar A, said shaft carrying the brush F, which is adapted to be projected up the flue or chimney, and upon the lower end of the

shaft E is arranged a beveled gear G, which meshes with a similar gear H, mounted upon the end of the shaft I, journaled in hanger-brackets K, depending from the bar A and provided with a crank L at the outer end, by means of which the shaft can be revolved and its rotary motion transmitted through the gears to the rotary brush, thereby thoroughly cleaning the chimney. 55

A pan M is intended to be arranged upon the hearth and within the fireplace in order to catch the soot or dirt which is swept out by the rotary brush. 60

It will thus be seen that I provide an exceedingly cheap and simple construction of chimney-sweeper which can be set up in any fireplace and can be quickly and easily operated to sweep and clean any construction of chimney. 65

Having thus described my invention, what I claim as new, and desire to secure by Letters Patent, is—

1. In a chimney-sweeping device, a rotary brush adapted to be projected up the flue, a 75 bar or frame in which the shaft of the brush is journaled, said bar or frame being provided with adjustable feet, whereby it can be fitted in any size of fireplace, and the power-transmitting devices carried by the bar or frame 80 for the purpose of rotating the brush, substantially as shown and described.

2. In a chimney-sweeping device, the combination with the bar having adjustable feet at each end, of the rotary shaft journaled in 85 the said bar and provided with a brush at the upper end; and a beveled gear at the lower end, the shaft arranged at right angles to the vertical shaft and provided with a beveled gear at one end, the crank at the opposite end, 90 substantially as shown and described.

3. In a chimney-sweeping device, the combination with a bar, of the adjustable metallic feet at the opposite ends, the vertical shaft carrying the brush and beveled gear, the 95 horizontal shaft carrying the beveled gear, the crank, and the hanger-brackets, all arranged and adapted to operate, substantially as shown and described.

4. In a chimney-sweeping device, the combination with the bar having screws at the opposite ends, the metallic feet having longi- 100.

tudinal slots, and the winged nuts for securely holding the feet upon the ends of the bar, of the vertical shaft journaled centrally of the bar and having a brush at the upper end and 5 carrying a beveled gear at the lower end, the depending hanger-brackets, the rotary shaft journaled therein carrying the beveled gear

at the inner end, and the crank at the outer end, substantially as shown and described.

GEORGE W. MIDDLETON.
